UNITED STATES PATENT OFFICE.

JOHN B. ADDUCI, OF BOSTON, MASSACHUSETTS.

ASH-SIFTER.

1,300,234.

Specification of Letters Patent. Patented Apr. 15, 1919.

Application filed April 25, 1918. Serial No. 230,710.

To all whom it may concern:

Be it known that I, JOHN B. ADDUCI, a citizen of the United States, residing at Boston, in the county of Suffolk and State of 5 Massachusetts, have invented certain new and useful Improvements in Ash-Sifters, of which the following is a specification.

This invention relates to ash sifters, and especially that type of sifter designed to be 10 used indoors, in a cellar or basement. In constructing such sifters it is essential that provision be made for preventing dust escaping during the sifting operation, and also to allow for easy handling of the ashes and 15 cinders after the sifting operation has been finished. Another important essential is that the sifter be of durable construction but at the same time inexpensive. While the saving of coal is a leading factor in the use 20 of such devices the real motive for their use under ordinary conditions is the saving of money represented by the value of the fuel reclaimed by the sifting process. Therefore if the cost of the sifter is out of proportion to the value of the reclaimed product in terms of dollars and cents it fails 25 to accomplish the saving for which it is primarily intended.

I have endeavored to combine all of these 30 essential features in the one device so far as possible, and have also provided for the damping of the sifted cinders as when used dry much ash dust clings to them, as is well known by any one burning undampened 35 coal cinders, so that to provide means for preventing escape of dust only during the sifting process and then to allow the dust collected on the cinders and carried by them into the cinder receptacle to escape into the 40 cellar or basement is to defeat one of the main objects of devices of this type.

The invention consists in the novel features of construction hereinafter described, pointed out in the claims, and shown in the 45 accompanying drawings, in which:

Figure 1 is a vertical section through the complete device.

Fig. 2 is a section on the line 2—2 of Fig. 1.

50 Fig. 3 is a face elevation of a cinder receptacle, detached from the sifter.

Fig. 4 is a top plan view of the sifter.

In the drawings A designates a suitable ash receiving can, barrel, or other receptacle provided by the user, and on which 55

my sifter is designed to rest. The sifter consists of a rectangular casing 1, of either metal or wood and provided with a lid 2 60 slidable in the guideways 3. Outward movement of the lid is limited by a stop 4. The casing 1 is provided with a vertical slidable rear panel 5, forming the rear side of the sifter casing, and by drawing this slide upwardly ready access is had to the receptacle 6, without removing the sifter from position. The frame 6 carries a suitable mesh screen 6^a. The casing 1 has a flat bottom 8, of larger surface area than the cross section of the casing at the bottom, and said 65 bottom is centrally cut out as at 8^b so that the ashes falling through the screen will drop into the receptacle A. Suitable cleats 8^a secured to the underside of the bottom 8 hold it in place on the receptacle. In Fig. 2 70 the receptacle is indicated in dotted lines. At the front the lower portion of the receptacle or casing 1 is enlarged by extending the front wall outwardly as at 7, and below such extension it is cut out to form 75 a cinder exit 9.

Hung on the lower front portion of the casing 1, and detachably connected thereto is a cinder box 10.

To the upper side portions of this box 85 I secure false side members 11 which project over the sides of the casing 1 and the lower projecting corners of these members are cut out to form shoulders 12.

These members also aid in forming guides 90 for a slidable cover 15 for the cinder box. Between the side members the front of the cinder box, which is the side adjacent the casing 1, is cut out as at 13. A projecting beveled block 14 is carried by the bottom of 95 the casing 1 extending across the opening 9, and this block supports the lower end of the frame 6 and engages the lower edge of the cut out portion 13 of the box 10, the front 100 projecting edge of the base 8 engaging under the shoulders 12 of the members 11.

The cinder box is provided with supporting legs 16 and the bottom is perforated as at 17. Eyes 19 are carried by the sides of the box and on plates 20 secured to the sides 105 of the casing 1 are mounted hooks 21 to engage the eyes 19 and lock the box 10 to the casing, both box and casing being supported by the receptacle A.

In use the parts are interlocked and 110

mounted as shown in Fig. 1 and the ashes and cinders are thrown into the upper portion of the casing 1. A deflector 22 serves to direct the stream of ashes falling through 5 the screen into the receptacle A. The cinders pass out the opening 9 and into the box 10. Should the receptacle A become too 10 full, as is sometimes the case the slide 5 may be lifted and the surplus ashes removed 15 from the receptacle before lifting off the casing 1, thereby avoiding spilling the ashes over the floor on removing the casing.

When the sifting operation is completed 20 the cinder box is detached and is then supported on the legs 16. Before removing the cinders from the box water can be poured or sprinkled over them, by drawing outwardly the cover 15, and the surplus water instead of accumulating in the bottom of the 25 box with the dust washed from the cinders will drain out through the perforations 17, the legs 16 permitting a drip pan or bucket being inserted under the box.

The cinders may be kept if desired in 30 the box until used, and the receptacle A removed by itself and emptied.

The many advantages of a device so constructed will be obvious to those who have had occasion to make use of sifters of the 35 indoor type. The device can be employed out of doors where it will be handy in preventing ashes blowing over walks, grass plots and upon adjacent buildings.

After such sifting the cinder box can be 40 readily carried into the building and to the place where they are to be burned.

Copies of this patent may be obtained for five cents each, by addressing the "Commissioner of Patents
Washington, D. C."

What I claim is:—

1. The combination with an ash receptacle and a sifter casing adapted to rest thereon, of a cinder box having supporting 40 legs and a perforated bottom and cut away adjacent the top on one side, side members carried by the box and cut out to form shoulders, a base for the sifter casing adapted to interlock with said shoulders, a 45 beveled projecting block carried by the casing and projecting into the cinderbox opening, a slidable top for the cinder box, and means for locking the cinder box to the lower portion of the sifter casing. 50

2. A device of the kind described comprising a casing adapted to rest on and communicate with a suitable ash receiving receptacle, an inclined screen therein, said casing having an opening at the foot of said 55 screen, a beveled block supporting the lower end of the screen and projecting through said opening, a cinder box, means for locking the cinder box to the lower portion of the casing, said cinder box having a side 60 opening, the beveled block of the casing projecting into said opening, projecting vertical side members of the box adapted to overlap the sides of the casing and having their lower corners cut out to form shoulders, and a projecting base for the casing, the said shoulders engaging and resting on said base when the box is locked to the casing, as and for the purpose set forth. 65

In testimony whereof I affix my signature. 70

JOHN B. ADDUCI.
